CLAIM

The ornamental design for a shoe outsole, as shown and described.

DESCRIPTION

FIG. 1 is a front bottom perspective view of a shoe outsole showing my new design;

FIG. 2 is a bottom view thereof;

FIG. 3 is a rear bottom perspective view thereof;

FIG. 4 is an enlarged view of the claimed region in FIG. 2, shown in isolation; and,

FIG. 5 is a cross section taken through line 5-5 of FIG. 4. The broken lines in FIG. 5 represent an internal part of the shoe sole and form no part of the claimed design. The broken lines showing the remainder of the shoe represent unclaimed subject matter and form no part of the claimed design.
